UNITED STATES PATENT OFFICE

112,227

DESIGN FOR A SOAP HOLDER OR SIMILAR ARTICLE

John A. Zapf, Ottawa Hills, Ohio, assignor to Gerity Adrian Manufacturing Corporation, Adrian, Mich., a corporation of Michigan.

Application March 1, 1938, Serial No. 75,486

Term of patent 7 years

To all whom it may concern:

Be it known that I, John A. Zapf, a citizen of the United States, residing at Ottawa Hills, in the county of Lucas, State of Ohio, and United States of America, have invented a new, original, and ornamental Design for a Soap Holder or Similar Article, of which the following is a specification, reference being had to the accompanying drawing, forming part thereof:

I claim:

The ornamental design for a soap holder or similar article, as shown.

JOHN A. ZAPF.
